(57) **CLAIM**

(**) Term: **14 Years**

The ornamental design for a computer chassis for dual,
opposing main boards, as shown and described.

(21) Appl. No.: **29/118,970**

DESCRIPTION

(22) Filed: **Feb. 18, 2000**

FIG. 1 is a top perspective view of a computer chassis
showing our new design;

(51) LOC (7) Cl. **14-02**

FIG. 2 is a top perspective view thereof with the top panel
removed;

(52) U.S. Cl. **D14/356**

FIG. 3 is a front elevation view thereof;

(58) Field of Search D14/301, 356,

FIG. 4 is a rear elevation view thereof;

D14/361, 363, 365, 368, 439; 174/35 R;
361/816, 818, 683, 686, 753, 799, 800

FIG. 5 is a left side elevation view thereof;

(56) **References Cited**

FIG. 6 is a right side elevation view thereof;

U.S. PATENT DOCUMENTS

FIG. 7 is a bottom plan view thereof; and,

D319,225 S * 8/1991 Kline et al. D14/365

FIG. 8 is an exploded view thereof.
